BUFFING OR POLISHING WHEEL

Laurens W. MacFarland, Old Greenwich, Conn.,
and Stephen Krugloff, New York, N. Y.; said
Krugloff assignor to said MacFarland

Application November 28, 1939, Serial No. 306,478

16 Claims. (Cl. 51—193)

This invention relates to improvements in buffing or polishing wheels and in the construction of the individual sections of sectional buffing wheels, in the construction of individual segments forming such sections, and in the method of forming such segments.

One object of our invention is to provide an improved buffing wheel, or wheel section, having improved means for the attachment of a plurality of buffing segments or members.

Another object of this invention is to provide a plurality of rings or discs each having a series of pins or studs extending in an axial direction and spaced circumferentially around the ring in proximity to its outer peripheral edge, and a series of sockets or holes arranged in staggered relation to said pins or studs and adapted to receive the ends of pins or studs on an adjacent ring.

Still another object is to provide a buffing section comprising perforated buffing members and axially projecting pins extending through said perforations to center the said members, and the pins of adjacent sections being arranged in staggered relation to each other so as to dispose the buffing members in adjacent sections in such manner as to distribute the material of said members uniformly throughout the peripheral surface of the buff.

With these and other objects in view, the invention consists in the novel construction and arrangement of parts hereinafter described, illustrated in the accompanying drawings, and particularly pointed out in the appended claims, it being understood that various changes in the form and constructional details may be made without departing from the spirit of the invention or sacrificing any of the advantages thereof.

In the drawings:

Fig. 1 is a side elevation of a sectional buffing wheel, mounted upon a spindle, and shown partly in section;

Fig. 2 is a side view showing the assembly of the buffing segments in part of one section of a buffing wheel;

Fig. 3 is a similar view showing the disposition of the segments when in operation;

Fig. 4 is a view of the outer peripheral edge of one of the segments looking in the direction of the arrows 4—4 Fig. 3;

Fig. 5 is a view of one of the buffing segments before folding;

Fig. 6 is a view of the folded segment ready for assembly;

Fig. 7 is an enlarged detail section on the line 7—7 of Fig. 2;

Figs. 8 to 13 inclusive show a modified form of the invention; Fig. 8 being a view corresponding to Fig. 5, but showing a modified form of buffing member;

Fig. 9 is a side view of the same in folded position;

Fig. 10 is an edge view of the member;

Fig. 11 is a view showing one of the segments mounted on a retaining core ring;

Fig. 12 is a view corresponding to Fig. 3, but 10 showing a modified form of buffing elements and attaching means;

Fig. 13 is a side view of parts of the supporting means for the buffing members;

Fig. 14 shows a strip of multi-ply fabric from 15 which buffing segments of modified form are produced;

Figs. 15 to 18 inclusive show other forms of buffing segments, Figs. 15 and 16 being respectively side and edge views of a buffing brush segment; and Figs. 17 and 18 being corresponding views of another form.

Referring to Figs. 1 to 7 inclusive, the wheel (Fig. 1) consists of five buffing sections of similar construction, held between end plates 15, 16, 25

mounted upon the spindle 17, with a securing nut 18 in the well-known manner. The end plate 15 is formed on its inner face and in proximity to its outer peripheral edge with a series of axially projecting pins or studs 19 spaced at equal distances apart and adapted to receive the buffing segments 20, which latter consist of multi-ply

discs, Fig. 5, of fabric or other suitable material, which may be obtained by cutting the centers from larger discs in the manufacture of buffing sections having a central opening equal to the dimensions of the disc members 20. The plies 21

in superimposed relation are provided with an inner member or core 22 of string or other reinforcing material over which the plies are folded 40 as shown at Fig. 6, and the member thus formed

is provided with a line of stitching at 23 to enclose and retain the reinforcing core 22, and the plies are perforated at 24, 25, and are slit at 26.

The buffing member is then ready for assembly 45 and is placed upon adjacent pins 19 as shown at Fig. 2, the buffing members 20 being arranged in overlapping relation as shown. When a multi-

section wheel, as shown at Fig. 1, is required, discs or rings 27 are employed, see Fig. 7. Each disc or 50 ring 27 is provided with holes 28 for engagement

upon reduced ends 29 forming part of the studs or pins 19, and these ends 29 may be slotted at 30

in order to provide a certain amount of spring action whereby the ring 27 is held in assembled 55

relation to the disc 15. Each disc or ring 27 is also formed with pins or studs 31 similar to the pins or studs 19, but arranged equidistant between the holes 28 so that in assembled position 5 the pins or studs 19 are in staggered relation to the pins or studs 31. The studs 19 and holes 28 may be similarly disposed on the end discs 15, 16 and on the intermediate rings 27, so that these discs and rings are interchangeable and discs 10 such as 15, 16 may be employed in lieu of any of the rings 27 when so desired. Similar buffering segments 20 are assembled upon the projecting pins or studs 31, and by reason of the staggered relationship of the pins or studs 19, 31, above referred to, a uniform distribution of the material 15 of the buffering segments is insured throughout the peripheral surface of the sectional wheel. When the desired number of sections have been assembled, projecting ends corresponding to the ends 20 29 are engaged by perforations in the end plate 16, and when the nut 18 is screwed upon the spindle 17 the parts of the buffering wheel are retained in properly assembled position.

When the buff section is in use the overlapping 25 portions of the segments 20 (Fig. 2) move outwardly under centrifugal force and the buffering material then assumes the form shown at Fig. 3. This outward movement is a result of the slits 26 and of the mounting of the segments without 30 axial compression between adjacent plates or rings.

Referring to Figs. 8 to 13 inclusive, the segmental buffering elements in this case consist of a plurality of superimposed plies 36 of fabric or other material that may be cut from the center of a larger buffering disc, or may consist of a discarded buffering disc that has been worn down to a diameter too small for satisfactory use. The member comprising the plies 36 is perforated at 37, 38 and is then folded along a line 39 passing centrally through both perforations. A line of stitches 40 is then provided between said perforations so as to form an open-ended loop 42 for the reception of a retaining wire or core 41.

For the assembly of these buffering members an end plate 49 corresponding to the end plate 15 is provided with an annular series of axially projecting pins 50 equidistantly arranged in proximity to the outer periphery of the plate. The inner faces of these pins 50 are engaged by the core wire or spring ring member 41 which has hooked ends 52 for engagement over one of said pins, and said spring member 41 preferably engages grooves formed in the inner faces of the pins 50. The spring member 41 is adapted to be threaded through the loops 42 (Fig. 10) of the buffering members which are thus assembled in overlapping relation. By the use of intermediate discs or rings 55 having on one side face axially projecting pins 56 similar to the said pins 50 and having on the opposite side face a similar series of axially projecting pins 57 arranged in staggered relation to the pins 56. When the buff segment 60 shown at Fig. 11 is in use, the projecting side portions 58 tend to move outwardly by centrifugal force so that each member when in operating position at high speed assumes the form substantially as shown at Fig. 12.

70 Buffering segments for use in accordance with this invention may be produced without folding and Fig. 14 shows a multi-ply strip 32 of bias fabric or other suitable material which is perforated at 33 along both edges and is cut along 75 inclined lines 34 so as to produce wedge-shaped

blanks 35 with perforations suitably spaced for engagement by the pins 19, Fig. 2.

Figs. 15 to 18 inclusive show buffering elements in the form of Tampico brushes 63, 64 or other fibrous bunches so formed that they may be conveniently applied to the said pins 19. In the form shown at Figs. 15 and 16 the brush member 63 has an eye 60 while the member 64 shown at Figs. 17 and 18 has two eyes 61, 62 spaced to suit the spacing of the said pins 19. These brush members 63, 64 are made by lacing or stitching the bristles or fibres together at 65, and cement or other hardening composition may be employed in forming the eyes 60, 61, 62.

It has been heretofore proposed to provide 18 means whereby cooling or ventilating air may be passed inwardly in an axial direction through the body of a buffering wheel and from thence outwardly in a radial direction between buffering sections or segments, and although such ventilation 20 or air cooling is not an essential part of the present invention, the end plates 15, 16 and 49 may all be provided with air holes 59, so that air may pass inwardly into the interior of the wheel and the 25 form and arrangement of the pins or studs 19, 31, 50, and 57, are such that spaces are provided for the free passage of air outwardly in a radial 30 direction between adjacent buffering sections, or between adjacent segments, so that effective ventilation or cooling is insured.

Although the drawings and the above specification disclose the best modes in which we have contemplated embodying our invention, we desire to be in no way limited to the details of such disclosure, for in the further practical application 35 of our invention many changes in form and construction may be made as circumstances require or experience suggests, without departing from the spirit of the invention within the scope of 40 the appended claims.

What we claim is:

1. A sectional buffering wheel comprising an end plate for mounting and centering the buffering section, studs mounted on said plate and circumferentially spaced from each other in close proximity to the outer peripheral edge of the plate, a plurality of buffering segments, means whereby the buffering segments are each anchored between two adjacent studs, and means on the free ends of 50 the studs for engaging an adjacent section and for maintaining between the sections axial spacing to permit turning movement of the segments upon the studs.

2. A sectional buffering wheel comprising an end 55 plate for mounting and centering the buffering section, studs projecting axially from said plate and circumferentially spaced from each other in proximity to the outer peripheral edge of the plate, a plurality of buffering segments, openings at the 60 inner parts of the buffering segments whereby such segments are penetrated and anchored to the studs, and means on the studs for engaging and centering an adjacent section and maintaining a predetermined axial distance between the sections.

3. A sectional buffering wheel comprising an annular buffering section having a plurality of buffering members of flexible material, rings having axially projecting studs spaced from each other in a circumferential direction for anchoring the said buffering members, and means for maintaining uniform spacing between said rings for the accommodation of the buffering members to permit independent turning movement of the said members 75

under centrifugal force while the buff is in operation.

4. In a sectional buffing wheel, a buffing section comprising a plurality of similar buffing members arranged circumferentially around the section, metallic rings supporting and centering the section, a plurality of axially projecting anchoring and spacing studs secured to one of said rings and engaging the second ring to maintain the spaced relation of such rings and to anchor the buffing members without axial compression, and holes in the said second member to receive the ends of said studs.

5. A sectional buffing wheel comprising annular members for centering and supporting the buffing sections, each buffing section comprising a circumferential series of buffing segments, a circumferential series of anchoring studs spaced from each other in proximity to the outer peripheral edge of a centering member, and spring members on said studs for engaging an adjacent centering member.

6. A sectional buffing wheel comprising rigid annular members for supporting and centering the buffing sections, projecting studs for mounting the buffing members upon the centering members, means on said studs for maintaining said centering members in spaced relation to each other, and two spaced perforations in each buffing member penetrated by two adjacent studs to anchor each member in its section.

7. A sectional buffing wheel comprising rigid annular members for supporting and centering the sections, a plurality of buffing segments in each section, axially projecting studs for mounting the buffing segments upon the centering members, means on said studs for maintaining said centering members in axially spaced relation to each other, and perforations in the buffing segments whereby the said studs penetrate and anchor the segments in the sections, the studs in adjacent sections being staggered in relation to each other to uniformly distribute the material in the buffing sections throughout the circumference of the sectional wheel.

8. In a sectional buffing wheel, buffing sections each comprising a plurality of circumferentially arranged buffing members, a metallic centering ring for said members, an annular series of spaced projecting studs provided on the side face of the ring for anchoring the buffing members, a series of sockets in said ring for engaging the studs on an adjacent ring, the sockets and studs being arranged in staggered relation to each other in each ring to align each stud in the assembled wheel in alignment with the stud in the second section therefrom, and means independent of the buffing members for maintaining the spaced relation of the rings from each other in an axial direction to permit free turning movement of the buffing members upon their anchoring studs.

9. In a sectional buffing wheel, an annular buffing section of flexible material comprising individual circumferentially arranged portions, a pair of perforations in each portion, an annular series of anchoring studs circumferentially spaced from each other with two adjacent studs penetrating the perforations of each buff portion, annular supporting and centering members carrying said studs, means for maintaining spaced relation between said annular members in an axial direction to allow limited turning movement of the buffing portions upon the studs, and means for

insuring staggered relationship between the buffing portions in adjacent sections.

10. In a sectional buffing wheel, an annular buffing section of flexible material comprising a series of circumferentially arranged segments of buffering material, openings in the segments near the inner extremities thereof, an annular series of axially projecting anchoring studs circumferentially spaced from each other for anchoring the said segments through the medium of said openings, annular supporting members carrying said studs, means for resisting clamping pressure in the buff and maintaining spaced relation between said annular members in an axial direction to allow limited turning movement of the buffing segments under centrifugal force, and means for insuring staggered relationship between the buffing segments in adjacent sections.

11. A buffing wheel section comprising an annular metallic member for supporting and centering the buff upon its spindle, an annular series of studs projecting in an axial direction from said annular member in proximity to its outer peripheral edge, and a plurality of buffering members forming the said section and being of substantially semi-circular form and having two perforations with a split extending therebetween, the perforations being adapted to receive two adjacent studs so that the member may turn upon said studs and the outer corners of the buff portions may swing outwardly towards the periphery of the buffs to pucker the material of the buff and provide a substantially uniform circumferential buffering surface.

12. In a buffering section, a plurality of buffering segments each comprising a plurality of flexible discs folded along a center line, a flexible reinforcing core at the center part of the fold, a slit extending centrally at right-angles to the said core, a perforation extending through the material at each side of the slit, two axially projecting studs spaced from each other in a circumferential direction for engaging said perforations to anchor the buffering member and permit limited turning movement of said member under centrifugal force, and means for supporting said studs upon the spindle.

13. A buffering segment for a buffering wheel of the character described comprising a multi-ply structure of flexible buffering material folded along its central line, reinforcing stitches extending along the central part of the fold, a split formed in the center part of the buff perpendicular to the fold, and two perforations located in proximity to the fold, for the reception of two spaced anchoring studs.

14. A buffering segment for a buffering wheel of the character described comprising a multi-ply structure of flexible buffering material of substantially circular form folded along its central line, reinforcing stitches parallel to the central part of the fold, a strengthening core enclosed by said stitches, a slit extending through the fold in the center part of the buff and perpendicular to the fold, and two perforations located in proximity to the fold, one on each side of the slit, for the reception of anchoring studs.

15. In a sectional buffering wheel, a buffering section comprising a metallic ring member, a series of axially projecting studs on said ring, an arcuate spring rod retained by said studs, and a plurality of flexible buffering members anchored by said rod and spaced from each other by said studs.

16. In a buffering wheel, an annular buffering section comprising a plurality of buffering segments arranged circumferentially around the section and folded to form loops at their inner extremity, a retaining core extending through said loops, a plurality of studs for retaining said core, a metallic ring carrying said studs, and means on

said studs for maintaining the spaced relation between adjacent rings in an axial direction to permit limited movement of the buffering segments upon the retaining core.

L. W. MACFARLAND.
STEPHEN KRUGLOFF.
